UNITED STATES PATENT OFFICE.

EUGENE NEUMAIER, OF NEW YORK, N. Y.

DESIGN FOR A CURTAIN.

Application filed May 4, 1928. Serial No. 26,568. Term of patent 3½ years.

To all whom it may concern:

Be it known that I, EUGENE NEUMAIER, a citizen of the United States, and residing in the county of New York, of the city of New York, in the State of New York, have invented a new, original, and ornamental Design for Curtains, of which the following is a specification, reference being had to the accompanying drawing, forming a part thereof.

The figure is a view of a curtain showing my new design enclosed within the broken lines, which design is repeated over the en-

tire curtain including the ruffle. The design consists of bands of color crossing one another at right angles and the intensity of each band shades off from a deeper color to a lighter color as represented by the spacing of the lines.

I claim:

The ornamental design for a curtain substantially as shown and described.

This specification signed this 2nd day of May, 1928.

EUGENE NEUMAIER.
